W. HEUSSER

ARMATURE AND MOUNTING FOR VIBRATORY UNITS AND THE LIKE

Filed May 24, 1926

Patented Jan. 17, 1928.

1,656,484

UNITED STATES PATENT OFFICE.

WILFRID HEUSSER, OF SALT LAKE CITY, UTAH.

ARMATURE AND MOUNTING FOR VIBRATORY UNITS AND THE LIKE.

Application filed May 24, 1926. Serial No. 111,455.

This invention relates to an armature and mounting for radio receivers and the like, and constitutes an improvement on the construction shown in my U. S. Patent No. 5 1,583,882, granted May 11, 1926. Its principal objects are to provide:

First. An oscillating armature so delicately poised that the frictional resistance of its bearings shall be reduced to a minimum, 10 thereby rendering the armature responsive to the slightest actuating forces.

Second. A mounting which, notwithstanding its delicacy, shall cause the armature to be held so securely and positively, that the 15 most severe usage shall not impair its operative properties.

Third. An armature which shall be held to its bearings by a constant predetermined spring pressure so that there shall be not the 20 slightest lost motion therein.

Fourth. A structure which shall be comparatively economical to manufacture when considering its refinement of design.

In attaining the objects just outlined, I 25 provide a spool structure preferably in accordance with that described in my application for U. S. patent for an improved vibratory unit whose filing date is even herewith.

Within the sleeve of the spool, I provide 30 an armature which extends from end to end thereof in the usual manner. Intermediate or interjacent the ends of the armature and projecting from the sides thereof, are two oppositely disposed projections or lugs whose 35 edges, transverse to the length of the armature, are formed to a sharp knife edge of general V-form which are arranged to take their bearing in notched members fixed in the spool sleeve. Between the bearing lugs 40 of the armature is an opening with a knife edge facing in the direction opposed to the knife edges of the bearing lugs.

A tie member, which may consist of a bent wire having two branches with a short bend 45 between them, is passed through the said opening so that the bend thereof shall engage the knife edge of the opening, while the branches extend to the outside of the spool where they may be engaged by a tensioned 50 spring member which serves to pull the armature with its knife edge lugs securely against the bearings thereof. The intermediate knife edge bearing lies substantially on a straight line joining the knife edge 55 bearings of the side lugs, so that a perfect pivot action is secured for the armature,

with only an infinitesimal degree of friction.

The armature, thus mounted, is highly sensitive and of unlimited durability.

The features of this invention for which 60 the protection of Letters Patent is desired, are collectively grouped in the claims which conclude this specification.

In the drawing which shows a desirable 65 form of this invention:

Fig. 1 represents a plan, the spool being in horizontal section on line 1—1 in Fig. 2;

Fig. 2, an elevation in the direction of the arrow 2, Fig. 1, reflected from a mirror plane;

Fig. 3, a section on line 3—3, Fig. 1;

Fig. 4, an enlarged fragmentary section taken as indicated on line 4—4 in Fig. 1.

Referring to the drawing, 10 indicates the sleeve of the spool, 12 the flanges thereof, 14 the magnetic conductors and 15 the pole pieces.

The armature 16 is oscillatingly mounted within the sleeve and extends from end to end thereof in the direction perpendicular 80 to the axis of oscillation.

Pins 17 pass through the sleeve and pole pieces preferably at, or near, the sides thereof, and are secured in place by light riveting as shown at 18 in Fig. 4. V-shaped 85 notches having the intersecting inclined faces 19, at their vertices from the bearings for the armature 16. The armature may have its front portion somewhat wider than its rear portion, thus forming an offset or 90 lug on either side, each offset having the inclined faces 21, which intersect and form substantially a sharp knife-edge.

The angle between faces 21 is less than the angle between faces 19, so that there shall 95 always be sufficient clearance to allow unobstructed movement for the armature.

The two knife edges of the armature should coincide with the straight line joining them to each other. This line constitutes the axis of oscillation of the armature.

Between the two said edges and on the same straight line, lies a third knife edge 105 24, in this instance, a point in the circumferential intersection of the beveled surfaces, defining the opening 25, to which the said straight line is tangent.

Through the opening 25 extends the tie 110 26 having the two branches 26—1 with the connecting bend 26—2 and the eyelets 26—3. An equalizing yoke 27 having the curved

arms 27—1 united by the bend 27—2 engages the tie 26 in a manner clearly shown in Fig. 3, where the arms 27—1 extend through the eyelets 26—3.

5 A spring bar 28 preferably made of phosphor bronze wire engages the yoke 27 in its bend 27—2, and is tensioned by having its two ends sprung back to rest in the outboard cradles 30 which latter are supported by the integral legs 30—1 having the feet 30—2. These feet are tightly fitted into one conductor 14 and one flange 12 of the spool, and thus securely hold the tensioning assemblage for the armature and therefore the armature itself as well.

It will be noticed that after the assemblage is made, there will be nothing to deteriorate or get out of order, excepting through breakage.

20 To be specific: (a) The friction in the armature bearings is so infinitesimal that there may be said to be no wear at all. (b) No movement is required of the members of the spring-rigging, so that all flexing is 25 static, and therefore no part of the structure is subject to crystallization. (c) Lost motion in the bearings of the armature can never occur.

Hence, an instrument constructed in accordance with this invention should have 30 unlimited durability, subject only to considerations of abuse or deteriorating influences from the outside.

For convenience in designation, the knife-like edges defined by beveled faces 21, may be called "primary" and the knife-like edge 24 be called "secondary".

While a typical embodiment of this invention is herein shown and described, it 40 should be clearly understood that all the detailed parts thereof, may or may not, appear in the preferred forms, and also, that the preferred forms may be varied from time to time, depending upon the circumstances and conditions governing and governed by, the development of this invention and the arts to which it is incident, therefore the scope of this invention may be ascertained from the claims in which its 45 spirit is generalized.

Having fully described my invention, what I claim is:

1. An armature having knife edge portions spaced apart from each other substantially along an axis of oscillation, said axis of oscillation located interjacent the oscillating extremities of the said armature, and a mounting having bearings arranged to operatively receive said knife edge portions.

60 2. An armature having knife edge portions spaced apart from each other substantially along an axis of oscillation, said axis of oscillation located interjacent the oscillating extremities of the said armature, a mounting having bearings arranged to re-

ceive said knife edge portions and a rigging arranged to hold said armature against its bearing under a spring tension.

3. An oscillating armature, bearings for the armature, and a spring rigging operative 70 to thrust said armature against its bearings, said spring rigging comprising a tie engaging the armature, said tie having outwardly extending branches, a yoke having arms engaging the said branches and a tensionable 75 member engaging said yoke.

4. An armature having primary knife-like edges spaced apart from each other, a secondary knife-like edge between the said primary edge, bearings for said edges, and holding means operative upon said secondary edges, said holding means comprising a tie having branches straddling the plane of the armature and forming a crotch, said crotch engaging said secondary edge, and means for exerting a pull on said branches.

5. An armature having an axis of oscillation, primary and secondary bearing edges lying substantially on said axis, the said secondary intermediate the said primary, bearings for the said primary, and a spring rigging operative upon the said secondary, said rigging comprising a tie having branches forming a crotch, an equalizing yoke having arms engaging the said branches and a tensioned member engaging said yoke.

6. An armature and mounting for vibratory units and the like, comprising a spool structure, an oscillating armature having primary edges located upon opposite sides 100 of said armature, bearings for said edges within the spool, a secondary edge located intermediate the said primary edges substantially in the axis of oscillation, a tie operative to hold said primary edges to said bearings, and tensioned members operatively engaging said tie.

7. An armature and mounting for vibratory units and the like, comprising a spool having a sleeve, bearings spaced apart from 110 each other in said sleeve, an oscillating armature having primary edges on opposite sides thereof arranged to engage said bearings, a secondary edge intermediate the said primary edges substantially in the axis of 115 oscillation, a spring rigging engaging said secondary edge operative to press said primary edges against their bearings, and supporting members for said spring rigging disposed upon said spool.

8. A spool, an oscillating armature having edge members upon opposite sides of the armature, bearings for said edge members within said spool, and means for pressing said edge members against said bearings.

9. An armature having knife edge portions spaced apart from each other and located upon opposite sides of the armature, a spool with bearings arranged to receive said knife edge portions and a spring rigging 130

mounted on said spool arranged to hold said armature against its bearings.

10. An armature having edges, a structure having bearings engaging said edges, a tensioned spring bar, outboard bearings supporting said spring bar, and connecting members extending from said tensioned bar to said armature.

11. An oscillating armature, a tie having 10 a crotch engaging said armature, branches extending from said crotch, a yoke engaging said branches, a tensioned bar engaging said yoke, and outboard bearings supporting said tensioned bar.

12. An armature, bearings on opposite sides of said armature, interjacent its ends, a tie engaging said armature between said bearings, a yoke engaging said tie, a tensioned spring bar engaging said yoke, and 20 outboard bearings supporting said spring bar.

13. A spool having a sleeve, and flanges

carried by said sleeve, an oscillating armature mounted within said sleeve, a tie having a crotch engaging said armature, branches 25 extending from said crotch, a yoke engaging said branches, a tensioned bar engaging said yoke, and bearings spaced apart from the outer face of one of said flanges, said bearings supporting said tensioned bar. 30

14. A spool having a sleeve, and flanges carried by said sleeve, an oscillating armature mounted within said sleeve, bearings on opposite sides of said armature, interjacent its ends, a tie engaging said armature between said bearings, a yoke engaging said tie, a tensioned spring bar engaging said yoke, and bearings spaced apart from the outer face of one of said flanges, said bearings supporting said tensioned bar. 40

In testimony whereof I sign my name hereto.

WILFRID HEUSSER.
